UNITED STATES PATENT OFFICE.

ARTHUR H. STODDARD, OF BOSTON, MASSACHUSETTS, ASSIGNOR TO THE BOSTON DENTAL MANUFACTURING COMPANY, OF SAME PLACE.

LOCKING DEVICE FOR THE FLASKS OF DENTAL VULCANIZERS.

SPECIFICATION forming part of Letters Patent No. 436,009, dated September 9, 1890.

Application filed December 5, 1889. Serial No. 332,675. (No model.)

To all whom it may concern:

Be it known that I, ARTHUR H. STODDARD, a citizen of the United States, and a resident of Boston, in the county of Suffolk and State 5 of Massachusetts, have invented certain new and useful Improvements in Locking Devices for the Flasks of Dental Vulcanizers, of which the following is a specification.

My improvements are directed particularly 10 to the devices whereby the vulcanizing-flask is kept together under the necessary pressure during vulcanization.

In the accompanying drawings, Figure 1 is a plan view of the top of a vulcanizer with 15 operating-handle removed; Fig. 2, a vertical section on the line $x-x$ of Fig. 1 of the vulcanizer, including the vulcanizing-flask in position therein; and Fig. 3 is a plan view of the flask and the device by which it is held together.

As a means of clamping and holding the two parts of the flask together, I employ a spring A, formed of a piece of spring metal, having a lower member a embracing the bottom of the flask and an upper member a' extending over the top of the flask. In conjunction with this upper member I provide locking-cams B, pivotally attached to the said upper member and bearing upon the top of the flask. These locking-cams, when thrown in one direction, force the cover or upper portion of the flask tightly against the lower portion, and the apparatus is in this condition during vulcanization. When it is desired to open the flask, this may readily be done by throwing the locking-cams in the reverse direction, or so as to unlock them, when the flask can be easily taken out and opened.

I have shown two locking-cams arranged at 40 either side of the upper member a' of the clamping-spring. A single cam placed in the

center of the end of the spring might be employed, but would not, in my judgment, operate as satisfactorily.

Furthermore, by pivoting the levers upon 45 the cover, as distinguished from pivoting them upon the pot, as has heretofore been done, I obtain an important practical advantage, in that when the cover with the levers is removed and placed one side no parts are left hanging 50 loosely upon the pot to get in the way of the operator or to interfere with his handling of it.

I am aware that spring-containing devices have been employed heretofore for holding 55 the parts of a flask together during vulcanization, and I make, therefore, no claim, broadly, to the use of a spring for this purpose. I believe, however, that the specific construction of spring-plate operated by a locking and 60 unlocking cam is novel with myself for the purposes stated.

I claim—

The herein-described improvement in vulcanizers, consisting of the spring A, having a 65 lower member a to embrace the under side of the flask and an upper member a' extending over the upper portion of the flask, and locking-cams pivotally connected with the said upper member of the spring and arranged to 70 bear against the upper portion of the flask, whereby the parts of the flask may be locked together under spring-pressure and may be released from pressure when desired.

In testimony whereof I have hereunto subscribed my name this 29th day of November, A. D. 1889.

ARTHUR H. STODDARD.
